METHOD OF AND APPARATUS FOR DIS-
CHARGING FIRE EXTINGUISHING ME-
DIUMSEric Geertz, Aurora, Ill., assignor to Cardox Cor-
poration, a corporation of Illinois

Application April 27, 1938, Serial No. 204,676

17 Claims. (Cl. 169—11)

This invention relates to new and useful improvements in a method of and apparatus for employing carbon dioxide as a fire extinguishing medium.

5 Fire extinguishing systems which are intended to have available for use large quantities of carbon dioxide as an extinguishing medium store the carbon dioxide as a liquid in a bank or battery of cylinders. These cylinders are connected 10 in parallel to a common header or header arrangement so that the carbon dioxide may be discharged as desired from the various cylinders. The temperature of the liquid carbon dioxide stored in the cylinders is permitted to vary in 15 accordance with variations in the temperature of the surrounding atmosphere. The carbon dioxide is discharged from the tops of the several cylinders through the pipes of the system in the form of gas and is thus released at the location 20 of the fire.

It is a well known fact that the discharge of carbon dioxide gas from the top of a container will cause vaporization of a like amount of liquid remaining in the container. This vaporization 25 within the container effects refrigeration of the remaining liquid. If the discharge of gas from the top of the container is continued for a sufficient length of time to lower the temperature of the remaining liquid to the point at which solid 30 carbon dioxide is formed, —70° F., the remaining liquid will solidify and discharge must cease. Continuous discharge of approximately three-quarters of the original quantity of liquid carbon dioxide will produce a temperature drop of the 35 character referred to above so that the remaining one quarter will not be available for use.

It has been determined that liquid carbon dioxide discharged at a sub-atmospheric temperature is much more effective and possesses many 40 advantages over carbon dioxide discharged as a gas from liquid stored at atmospheric temperature. For example, liquid carbon dioxide discharged at from 0° F. to —50° F. will afford a much higher percentage of yield of snow when 45 discharged to the atmosphere than will gas discharged at atmospheric temperature. Theoretically, gas released at 70° F. can produce 29% snow, while liquid released at 0° F. can produce 60% snow. Lower temperatures, of course, 50 can produce even higher percentages of snow. It will be appreciated that this increased yield of snow will provide a heavier blanket over the fire and will thereby be more effective in excluding oxygen from the fire, for it will not be 55 placed by the natural air currents rising from

the fire. The increased yield of snow also will provide greater mass which permits the discharge to be directed at the fire with greater velocity for penetrating rising air currents and projected greater distances. The lower temperature of the liquid carbon dioxide has a much greater cooling effect on the material being consumed by the fire and thereby is more effective in preventing re-flash and will permit the fire fighters to more closely approach the fire. 10

It is the primary object of this invention to provide a method of and apparatus for materially improving the total effectiveness of a quantity of carbon dioxide as a fire extinguishing medium when stored at atmospheric temperature and its 15 corresponding vapor pressure.

A further object of the invention is to provide an improved method of and apparatus for releasing carbon dioxide from one or more cylinders in which it is stored at atmospheric temperature for fire extinguishing purposes. 20

Other objects and advantages of the invention will be apparent during the course of the following description.

In the accompanying drawing forming a part 25 of this specification and in which like numerals are employed to designate like parts throughout the same,

Figure 1 is a diagrammatic view of a fire extinguishing system embodying this invention. 30

Figure 2 is a similar view to Fig. 1, but illustrates a form of automatic control which has been added to the system of Fig. 1.

In the drawing, wherein for the purpose of 35 illustration are shown the preferred embodiments of this invention, and particularly referring to Fig. 1, the reference character 5 designates the cylinders, or other containers, which are arranged in a bank or battery in any desired 40 and most suitable manner. These cylinders 5 are intended to be charged with liquid carbon dioxide. They are intended to form a part of and constitute a source of supply for a fire extinguishing system which affords protection for 45 any and all types of articles, apparatus and enclosed spaces in connection with which a fire hazard may exist. The cylinders and the liquid carbon dioxide stored therein are directly subjected to changes in temperature of the surrounding atmosphere and for that reason, the liquid carbon dioxide is stored at atmospheric 50 temperature and its corresponding vapor pressure.

The tops of all of the cylinders 5 are suitably 55

connected with and in communication with a common header 6 which extends to and communicates with the interior of the casing 7 of a suitable three-way valve which further includes the rotatable plug 8 having formed therein the right angularly arranged passageway 9.

A second header 10 is connected with and placed in communication with the bottom portions of all of the cylinders 5 by means of the 10 couplings or attaching devices 11. This header 10 also extends to and is placed in communication with the interior of the valve casing 7.

A pressure indicating gauge 12 is placed in communication with the header 6 so that the 15 person in charge of this fire extinguishing system may determine at all times the vapor pressure of the carbon dioxide within the cylinders 5 and the header 6. A manually operable valve 13 is positioned within the header 10 between 20 the battery of cylinders 5 and the valve 7. This manually operable valve 13 is employed for varying the rate of discharge through this header. In other words, this valve 13 may be manipulated to provide a maximum flow through the 25 header 10, which will correspond with the flow through the header 6, or the valve 13 may be manipulated to restrict or retard the flow through the header 10 so that it will be less than the flow through the header 6.

30 The reference character 14 is intended to designate diagrammatically any space, article, apparatus or the like which requires fire protection. A common discharge line 15 extends from the valve 7 to the space, etc., 14, and discharges 35 thereinto through the diagrammatically illustrated nozzle, or the like, 16.

The mode of operation of this fire extinguishing system will be described as follows:

When a hostile fire exists in space 14 which 40 must be extinguished by means of this system, the operator or attendant adjusts the plug 8 of the valve 7 into the position shown in Fig. 1, from a position, not shown, where the terminals of the passageway 9 are placed out of communication with any two of the lines 6, 10 and 15. This positioning of the valve plug 8 brings about discharge of carbon dioxide gas through the header 6 and the discharge line 15 to the nozzle 16 by means of which it is directed onto the fire. 45 For every pound of gas which is discharged from the cylinders through the header 6, a pound of liquid carbon dioxide will evaporate in the cylinders. This evaporation of liquid carbon dioxide in the cylinders occurs as a result of absorption 50 of heat from the liquid carbon dioxide remaining in the cylinders and from the walls of the cylinders. This absorption of heat from the remaining liquid carbon dioxide functions to cool or refrigerate the same. The temperature 55 of the remaining liquid carbon dioxide continues to drop as long as the carbon dioxide gas is permitted to flow from the tops of the cylinders through the header 6 and on to the point of discharge relative to the fire. The vapor pressure 60 of the carbon dioxide within the cylinders also drops or reduces in value in proportion to the lowering of the temperature of the remaining liquid carbon dioxide. The attendant of the system, therefore, can determine the drop in 65 temperature of the remaining liquid carbon dioxide by watching the pressure gauge 12 which will indicate the drop in vapor pressure within the cylinders. When the pressure drops to the desired value, which corresponds with the de- 70 sired sub-atmospheric temperature, the attend- 75

ant will manipulate the plug 8 of the valve 7 for moving the passage-way 9 out of communication with the header 6 and into a position, not illustrated, which will establish communication between the header 10 and the common discharge line 15. In this position, the discharge of carbon dioxide gas from the tops of the cylinders 5 will cease and liquid carbon dioxide at the desired sub-atmospheric temperature will be discharged from the bottom portions of the cylinders through the header 10 and the common discharge line 15 to the nozzle 16 where it will be fed to the fire.

As has been stated above, liquid carbon dioxide at a suitable sub-atmospheric temperature produces a much higher yield of snow than carbon dioxide gas discharged at atmospheric temperature. The discharge of this low temperature carbon dioxide liquid may continue until the fire is extinguished.

In the use of fire extinguishing systems of this character, there frequently arises a need for at least two different rates of discharge of the fire extinguishing medium. It frequently is very desirable to rapidly discharge the medium to 25 flood the area attacked by fire in order to promptly extinguish the flame and superficial burning and to then materially reduce the flow of the fire extinguishing medium in order to keep the percentage of medium high enough to extinguish glowing and smoldering fire. The valve 13 is provided in the header 10 for this purpose. This valve may be adjusted and left in a condition which will bring about a delay or reduction in the discharge of liquid carbon dioxide through the header 10 as compared to the rate of discharge through the header 6. If it is not desirable to operate the system in this manner, the valve 13 normally may be set to provide a maximum rate of discharge through the header 40 10 which will correspond with the rate of discharge through the header 6. At a proper time, during the procedure of extinguishing the fire in the space 14, the valve 13 may be manipulated to retard the rate of flow of liquid carbon dioxide 45 at a sub-atmospheric temperature through the header 10.

The fire extinguishing system disclosed in Fig. 2 differs from the system disclosed in Fig. 1 only to the extent that an automatic valve is 50 provided for the valve 7 in the first described system.

The system of Fig. 2, therefore, includes a suitable bank or battery of cylinders 5 with a common header 6 connected to the tops of all of the cylinders and a common header 10 connected to the bottom portions of all of the cylinders by means of the connection 11. The header 6 is provided with a pressure gauge 12 to enable an attendant to determine at all times the vapor 60 pressure of the carbon dioxide stored in the cylinders 5. The headers 6 and 10 extend to branches 17 and 18, respectively, of a valve casing 19. A common discharge line 20, having a manual control valve 21, extends to the location which is to 65 be protected from fire by the system.

The automatic control feature of the system includes a cylinder 22 which has positioned there-in a suitably packed piston 23 which is loaded or normally urged in one direction by means of 70 the spring 24. The piston rod 25 projects outwardly of the cylinder 22 and has a rack 26 formed on its projecting portion. This rack 26 meshes with the teeth of a pinion 27 which is suitably secured to the stem 28 of the rotatable 75

valve body or plug positioned within the valve casing 19. The end of the cylinder 22 which faces the top or outer surface of the piston 23 is connected by a branch 6a to the top header 6.

5 A suitable hand valve 13 is provided in the header 10 in the same manner as the valve 19 of the system shown in Fig. 1.

The operation of this modified form of fire extinguishing system will be described as follows:

10 The valve 19 is, preferably, of the rotary plug type with an angularly shaped passage of the character disclosed in Fig. 1 and designated by the reference character 9. This is a conventional form of rotary plug valve construction and for 15 that reason, need not be specifically illustrated with reference to its details. The valve plug in Fig. 2 is normally positioned so that its angular passage-way will establish communication between the top header 6 and the common discharge line 20. The valve 21, which may be manually controlled as illustrated or which may be automatically controlled in any desired manner, is manipulated when a hostile fire occurs to permit flow of carbon dioxide through the discharge 25 line 20.

The vapor pressure normally existing in the cylinders 5 and the top header 6 will also exist in the cylinder 22 and will be high enough, at atmospheric temperature, to oppose the action 30 of the spring 24 tending to move the piston 23 toward the left-hand end of the cylinder 22. After the valve 21 is opened, carbon dioxide gas will be discharged from the tops of the several cylinders 5 through the top header 6 and the 35 valve 19 to the discharge line 20. This discharge of carbon dioxide gas will continue until vaporization of liquid carbon dioxide has lowered the temperature of the remaining liquid carbon dioxide to a value where the vapor pressure existing in the cylinder 22 will no longer be effective to oppose action of the spring 24. The spring, then, will move the piston 23 and its rod 25 with the result that the rack 26 will cause a 90° adjustment of the plug for the valve 19. This manipulation of the valve 19 will bring about a discontinuation of discharge of carbon dioxide gas from the cylinders 5 through the header 6 and will initiate a discharge of liquid carbon dioxide at the desired sub-atmospheric temperature 40 through the header 10 and the valve 19 to the main discharge line 20. It will be appreciated that with this type of automatic control, carbon dioxide gas will be discharged through the main line 20 until the temperature of the liquid remaining in the cylinders 5 has dropped to the 45 desired sub-atmospheric temperature and its corresponding vapor pressure, at which time the valve 19 will be manipulated to automatically effect change of discharge from gas to low temperature liquid. The valve 13, shown in Fig. 2, 50 may be manipulated in the same manner as that described in connection with the system illustrated in Fig. 1.

As has been explained above, liquid carbon dioxide released to the atmosphere at a low temperature will produce a considerably higher percentage of snow than will be produced by carbon dioxide gas when released to the atmosphere at atmospheric temperature. The lower the temperature at which the liquid carbon dioxide is released, the greater the percentage of yield of snow. The spring 24, which loads the piston 23 against the force of the vapor pressure within the cylinder, may be of any desired strength so that the piston 23 will be actuated to adjust the valve 55 19 at any desired vapor pressure value. The

selected vapor pressure value, of course, will correspond with the desired sub-atmospheric temperature at which the liquid carbon dioxide is to be discharged.

It is to be understood that the forms of this invention herewith shown and described are to be taken as preferred examples of the same, and that various changes in the shape, size and arrangement of parts may be resorted to without departing from the spirit of the invention or the scope of the subjoined claims.

Having thus described the invention, I claim:

1. A method of employing carbon dioxide as a fire extinguishing medium which comprises storing liquid carbon dioxide at atmospheric temperature and its corresponding vapor pressure, effecting discharge of carbon dioxide gas from storage until the vaporization caused by such gaseous discharge has lowered the temperature of the remaining liquid to a desired sub-atmospheric temperature, and then effecting discharge of the carbon dioxide as a low temperature liquid. 20

2. A method of employing carbon dioxide as a fire extinguishing medium which comprises storing liquid carbon dioxide at atmospheric temperature and its corresponding vapor pressure, effecting discharge of carbon dioxide gas from storage until the vaporization caused by such gaseous discharge has lowered the temperature of the remaining liquid to a desired sub-atmospheric temperature, and then effecting discharge of all of the remaining carbon dioxide as a liquid 30 at the sub-atmospheric temperature obtained by said vaporization.

3. Carbon dioxide fire extinguishing apparatus comprising a battery of cylinders for receiving liquid carbon dioxide at atmospheric temperature and its corresponding vapor pressure, means for discharging carbon dioxide gas from said battery of cylinders to the atmosphere until the vaporization caused by said gaseous discharge has lowered the temperature of the liquid remaining in the cylinders to a desired sub-atmospheric temperature, and means for automatically effecting discharge of carbon dioxide liquid from said battery of cylinders to the atmosphere at said 40 sub-atmospheric temperature. 45

4. Carbon dioxide fire extinguishing apparatus comprising a container for liquid carbon dioxide at atmospheric temperature and its corresponding vapor pressure, means for discharging carbon dioxide gas from said container to the atmosphere until the vaporization caused by such gaseous discharge has lowered the temperature of the liquid remaining in the container to a desired sub-atmospheric temperature, and means for automatically effecting discharge of carbon dioxide liquid from said container to the atmosphere at said 50 sub-atmospheric temperature. 55

5. Carbon dioxide fire extinguishing apparatus comprising a battery of cylinders for receiving liquid carbon dioxide at atmospheric temperature and its corresponding vapor pressure, a header connected to the tops of all of said cylinders of the battery, a second header connected to the bottom portions of all of said cylinders, a common discharge line for both of said headers, means for effecting discharge of carbon dioxide gas from said battery of cylinders through the top header and the common discharge line, and means automatically operating, as a result of 60 refrigeration of the liquid remaining in said bank of cylinders to a desired sub-atmospheric temperature and corresponding vapor pressure by the vaporization of liquid during the discharge of 65 gas, to discontinue discharge of gas and to effect 70 75

discharge of liquid carbon dioxide from said bank of cylinders through the bottom header and said common discharge line.

6. Carbon dioxide fire extinguishing apparatus comprising a container for liquid carbon dioxide at atmospheric temperature and its corresponding vapor pressure, a gas discharge line connected to the container at a point above the normal liquid level of the same, a liquid discharge line connected to the container adjacent its bottom, a common discharge line for the aforesaid gas and liquid discharge line, means for effecting discharge of carbon dioxide gas from said container through the gas discharge line and the common discharge line, and means automatically operating, as a result of refrigeration of liquid remaining in said container to a desired sub-atmospheric temperature and corresponding vapor pressure by the vaporization of liquid during the discharge 10 of gas, to discontinue discharge of gas and to effect discharge of liquid carbon dioxide from said container through the liquid discharge line and said common discharge line.

7. A method of employing carbon dioxide as a fire extinguishing medium which comprises the steps of discharging to the atmosphere carbon dioxide gas from a confined quantity of both liquid and gaseous carbon dioxide, continuing said discharge until the vaporization of liquid resulting from said gaseous discharge has lowered the temperature of the remaining liquid to a desired sub-atmospheric temperature, and then effecting discharge to the atmosphere of the carbon dioxide as a low temperature liquid.

8. A method of employing carbon dioxide as a fire extinguishing medium which comprises the steps of discharging to the atmosphere carbon dioxide gas from a confined quantity of both liquid and gaseous carbon dioxide, continuing said discharge until the vaporization of liquid resulting from said gaseous discharge has lowered the temperature of the remaining liquid to a desired sub-atmospheric temperature, and then effecting discharge to the atmosphere of all of the remaining carbon dioxide as a liquid at the subatmospheric temperature obtained by said vaporization.

9. A method of employing carbon dioxide as a fire extinguishing medium which comprises the steps of discharging to the atmosphere carbon dioxide gas from a confined quantity of both liquid and gaseous carbon dioxide, continuing said discharge until the vaporization of liquid resulting from said gaseous discharge has lowered the temperature of the remaining liquid to from 0° F. to -50° F., and then effecting discharge to the atmosphere of the carbon dioxide as a liquid at the temperature obtained by said vaporization.

10. A method of employing carbon dioxide as a fire extinguishing medium which comprises the steps of discharging to the atmosphere carbon dioxide gas from a confined quantity of both liquid and gaseous carbon dioxide, and with the rate of flow of the discharging gas being sufficiently rapid to quickly extinguish the flame and superficial burning of the fire to be extinguished, continuing said discharge until the vaporization of liquid resulting from said gaseous discharge has lowered the temperature of the remaining liquid to a desired subatmospheric temperature, 70 and then effecting discharge to the atmosphere of the carbon dioxide as a low temperature liquid at a rate of flow which is reduced sufficiently to materially prolong the period of discharge.

11. A method of employing carbon dioxide as a fire extinguishing medium which comprises the

steps of discharging to the atmosphere carbon dioxide gas from a confined quantity of both liquid and gaseous carbon dioxide, continuing said discharge until the vaporization of liquid resulting from said gaseous discharge has lowered the 5 temperature of the remaining liquid to a desired subatmospheric temperature with its correspondingly low vapor pressure, and as a result of said lowering of the vapor pressure effecting discharge to the atmosphere of the carbon dioxide as a low temperature liquid.

12. Carbon dioxide fire extinguishing apparatus comprising a container for both liquid and gaseous carbon dioxide, a first discharge line connected to the normal vapor space of the 15 container, a second discharge line connected to the normal liquid space of the container, means for effecting discharge of carbon dioxide gas through the first mentioned line, and means automatically operating, as a result of refrigeration 20 of liquid remaining in said container to a desired subatmospheric temperature and corresponding vapor pressure by the vaporization of liquid during the discharge of gas, to discontinue 25 discharge of gas through said first line and to effect discharge of liquid carbon dioxide from said container through the said second line.

13. Carbon dioxide fire extinguishing apparatus comprising a container for both liquid and gaseous carbon dioxide, a first discharge line connected to the normal vapor space of the container, a second discharge line connected to the normal liquid space of the container, means for effecting discharge of carbon dioxide gas through the first mentioned line, means automatically operating, as a result of refrigeration 30 of liquid remaining in said container to a desired subatmospheric temperature and corresponding vapor pressure by the vaporization of liquid during the discharge of the gas, to discontinue 35 discharge of gas through said first line and to effect discharge of liquid carbon dioxide from said container through the said second line, and means in said second line for varying the rate of flow of the liquid carbon dioxide there- 40 through relative to the rate of flow of the gaseous carbon dioxide through the said first line.

14. Carbon dioxide fire extinguishing apparatus comprising a container for both liquid and gaseous carbon dioxide, a first discharge line 50 connected to the normal vapor space of the container, a second discharge line connected to the normal liquid space of the container, means for effecting discharge of carbon dioxide gas through the first mentioned line, means automatically 55 operating, as a result of refrigeration of liquid remaining in said container to a desired subatmospheric temperature and corresponding vapor pressure by the vaporization of liquid during the discharge of gas, to discontinue discharge of 60 gas through said first line and to effect discharge of liquid carbon dioxide from said container through the said second line, and means operating independently of either of the aforementioned means for varying the rate of flow of liquid carbon dioxide through the second mentioned line.

15. Carbon dioxide fire extinguishing apparatus comprising a container for both liquid and gaseous carbon dioxide, a first discharge line connected to the normal vapor space of the container, a second discharge line connected to the normal liquid space of the container, means for effecting discharge of carbon dioxide gas through the first mentioned line and thereby causing re- 75

frigeration of liquid remaining in said container to a desired subatmospheric temperature and corresponding vapor pressure, and means automatically operating, as a result of reduction in pressure in the said first line, to discontinue discharge of gas through said first line and to effect discharge of liquid carbon dioxide from said container through said second line.

16. A method of employing carbon dioxide as a fire extinguishing medium which comprises maintaining a plurality of independently confined charges of liquid carbon dioxide at atmospheric temperature and its corresponding vapor pressure, effecting discharge of carbon dioxide gas from each one of said charges until the vaporisation caused by such gaseous discharges has lowered the temperature of the liquid remaining in each charge to a desired subatmospheric tem-

perature, and then effecting discharge of carbon dioxide from each one of said charges as a low temperature liquid.

17. A method of employing carbon dioxide as a fire extinguishing medium which comprises maintaining a plurality of independently confined charges of liquid carbon dioxide at atmospheric temperature and its corresponding vapor pressure, effecting simultaneous discharge of carbon dioxide gas from all of said charges until the vaporization caused by said gaseous discharge has lowered the temperature of the liquid remaining in all of said charges to a desired subatmospheric temperature, and then simultaneously effecting discharge of all of the remaining carbon dioxide of all of said charges as a low temperature liquid.

ERIC GEERTZ.
